UNITED STATES PATENT OFFICE.

WILLIAM HERBERT SMITH, OF EAST MOLESEY, ENGLAND, ASSIGNOR TO TRIANGULAR CONSTRUCTION COMPANY LIMITED, OF EAST MOLESEY, ENGLAND.

PRESS FOR MOLDING PLASTIC SUBSTANCES.

Application filed June 6, 1923. Serial No. 643,739.

To all whom it may concern:

Be it known that I, WILLIAM HERBERT SMITH, a British subject, residing at The Bungalow, Imber Court, East Molesey, in the county of Surrey, England, have invented certain new and useful Improvements in Presses for Molding Plastic Substances, of which the following is a specification.

This invention relates to presses for molding plastic substances and is particularly applicable to presses for forming blocks or slabs of concrete and like substances.

An object of the invention is to provide an improved press having a double toggle operating mechanism.

A further object is to provide such a press wherein one toggle functions in applying the necessary pressure to the material in the mold and will hereinafter be referred to as the pressure toggle and the other toggle functions in stripping or ejecting the molded article from the mold and will hereinafter be referred to as the ejection toggle, the movable links of both toggles being connected at different points to a common transmission member in operative connection with a plunger.

In the preferred form of the press the movable plunger is connected to a link, which will be termed the transmission lever which is pivotally connected at its far end to the movable link of the pressure toggle and at an intermediate point to the movable link of the ejection toggle.

The press will be described in a form suitable for hand operation but it is to be understood that power operated means may be substituted for the hand levers described.

Although the invention is applicable to machines in which positive relative movement between pressure plate and mold is given at one end only, it is preferred to embody it in a machine in which such relative movement is given at both ends of the mold.

Other objects and features of the invention will be understood from the following description of a preferred form of press and from the appended drawings, wherein:—

Fig. 1 represents a side elevation of the machine, partly in section, the various levers

being shown in their positions during filling of the mold.

Fig. 2 represents a front elevation of the machine partly in section. 55

Fig. 3 is a diagrammatic view showing the various levers in their position at which the material in the mold is subjected to maximum compression.

Fig. 4 is a similar diagrammatic view at 60 the end of the ejection movement.

The press is provided with a mold A provided with a movable bottom plate B; this bottom plate is supported by a number of pressure rods C carried by a cross-head D 65 which is guided in the hollow standards E arranged at the sides of the machine. Two operating hand-levers are provided; one, the pressure lever F applies the pressure to the mold, and the other, the ejection lever G is 70 employed for ejecting the molded block.

Each of these hand levers is connected through a toggle linkage to a transmission lever H, and to ensure smoothness of action it is preferred to provide this linkage and transmission lever mechanism on both sides 75 of the machine.

The pressure lever F is pivoted on a shaft *j* and an extension *F*¹ thereof is connected by a link *J* with pressure toggles *K* one 80 of which is carried by a fixed pivot *K*¹ and the other of which is pivoted to the end of the transmission lever H.

The ejection lever G is pivoted upon a shaft *L* which carries an arm *M* pivoted to 85 a link *N* pivoted to the ejection toggles *O* the upper one of which is carried by a fixed pivot *P* and the lower of which is pivoted to the lever *H* by a pivot *h*.

A top pressure plate *Q* is carried by parallel motion links *R* normally held in raised position by a spring *S*. The lower link *R* carries a shackle provided with a bail *T* under which engages a hooked top pressure rod *U*. 90 95

The operation of the parts so far described may be summarized as follows:—

Referring to Fig. 1 the mold is first filled with concrete or other material to be molded which is conveniently stored in a hopper 100 *Z*. The top plate *Q* is then lowered and in so doing the hooked rod *U* snaps over the

bail T under the action of a spring a. The ejection toggle being closed, the pivot h acts as the fulcrum of the transmission lever H and as the pressure lever f is lowered pressure is applied through the toggles K to the pivot at the end of the transmission lever thus causing the cross-head D to rise and the bottom plate B positively to compress the material in the mold from the bottom thereof. The force applied at the top of the lever F is magnified three times; once by the lever itself, then by the toggle K and finally by the lever H, the pressure increasing as the material in the mold becomes more compacted.

As the transmission lever H moves downwards it exerts a heavy pull to be exerted on the rod U which thus causes a heavy pressure to be applied to the top pressure plate Q which therefore exerts a positive compression of the material in the top of the mold. This positive relative movement between the pressure plates and the mold at both ends thereof ensures homogeneity in the resulting block.

Fig. 3 represents the position of the levers at the point at which the toggles K reach dead centre and maximum pressure is exerted on the mold. Further depression of the lever F causes the toggles K to pass their dead centre and thus releases the pressure on the mold thus removing the grip of the hooked rod U upon the bail T. Immediately after this release of pressure a cam Y on the shaft j engages a roller X upon a bell-crank lever W connected by a rod V engaging the rod U, thus causing the latter to be pulled backwards clear of the bail T, whereupon the pressure plate Q rises under the action of the spring S.

The ejecting lever G is now raised and in so doing it breaks the toggle O, and, the pressure toggle remaining fixed in position just beyond dead centre shown in Fig. 4, the pivot h now functions as the fulcrum of the transmission lever H. The lever H thus moves further up carrying with it the bottom plate B and ejecting the molded block from the mold. The arrangement of the levers is such that the maximum ejecting pressure is exerted on the bottom plate B at the beginning of the ejection operation when the resistance to ejection has its maximum value.

The machine is shown with the mold designed for the manufacture of hollow blocks of triangular cross-section, for the formation of the apertures whereof cores e are employed and braced front members f, Fig. 2, provide the walls for the two shorter sides of the triangle.

It is, however, to be understood that blocks of rectangular or other suitable section, hollow or solid, may be formed with in the width capacity of the machine, the

thickness of the blocks being varied by adjusting the front or back member or both members of the mold and providing top and bottom pressure plates to conform to the size of block required. The lever mechanisms are such that the hand levers F, G tend to remain in their extreme positions.

To assist in moving the machine from one position to another, wheels g are preferably provided at the rear thereof.

As previously explained, the cross-head D from which the bottom plate B is operated is guided in hollow standards E arranged in the sides of the machine; these hollow standards are closed at the top by covers d and the guides are therefore protected from concrete or like gritty material falling on to them during use of the machine. The trouble commonly experienced with block machines due to clogging of the guide surfaces is therefore minimized.

I claim:

1. In a block molding press the combination of a mold adapted to contain the material to be molded a toggle mechanism adapted to apply pressure to the material, a second toggle mechanism adapted to eject the compressed material from the mold and a transmission member connected at different points to both said toggle mechanisms and fulcrumed about the point at which it is connected to the first while the second is operative.

2. In a block molding press the combination of a mold adapted to contain the material to be molded a toggle mechanism adapted to apply pressure to the material, a second toggle mechanism adapted to eject the compressed material from the mold, and a transmission member connected at different points to both said toggle mechanisms and fulcrumed about the point at which it is connected to the second while the first is operative.

3. In a block molding press the combination of a mold adapted to contain the material to be molded a toggle mechanism adapted to apply pressure to the material, a second toggle mechanism adapted to eject the compressed material from the mold, and a transmission member connected at different points to both said toggle mechanisms and fulcrumed, while either toggle is operative, about the point at which it is connected to the other.

4. In a block molding press, the combination of a mold adapted to contain the material to be molded, a toggle mechanism adapted to apply pressure to the material, a second toggle mechanism adapted to eject the compressed material from the mold, a transmission member connected at different points to both said toggle mechanisms and fulcrumed about the point at which it is connected to the first while the second is

operative, a pressure plate at each end of the mold and interconnecting mechanism causing the pressure plates to move in opposite directions relatively to the mold by the operation of the transmission lever.

5. In a block molding press, the combination of a mold adapted to contain the material to be molded, a toggle mechanism adapted to apply pressure to the material, a second toggle mechanism adapted to eject the compressed material from the mold, a transmission lever through which the movement of the toggle levers is transmitted to a pressure plate at one end of the mold, a hooked tension rod adapted to transmit motion to the pressure plate at the other end of the mold, and means for disengaging said tension rod from the pressure plate after the tension in the rod has been removed.

20. 6. A press for molding blocks of concrete or other plastic materials, comprising a pressure plate operatively connected to a transmission lever, a pressure operating lever, toggle mechanism connecting said pressure operating lever with said transmission lever, an ejection operating lever, a second toggle mechanism connecting said ejection operat-

ing lever with said transmission lever, and means for altering the fulcrum of said transmission lever according to whether a pressure movement or an ejection movement is required substantially as described.

7. A block molding press having a mold, a pair of pressure plates, a cross-head carrying one of said pressure plates, guiding means for said cross-head comprising hollow standards and means to cover the tops of said standards.

8. A press for molding blocks of concrete or other plastic materials comprising a pressure plate operatively connected to a transmission lever, a pressure operating lever, toggle mechanism connecting said pressure operating lever with said transmission lever, an ejection operating lever, a second toggle mechanism connecting said ejection operating lever with said transmission lever and means for altering the fulcrum of said transmission lever according to whether a pressure movement or an ejection movement is required substantially as described.

In testimony whereof I affix my signature.

WILLIAM HERBERT SMITH.
